CLOSURE CAP

Assad M. Malluk, New York, N. Y.

Application November 14, 1938, Serial No. 240,257

2 Claims. (Cl. 220—49)

The object of the invention is to provide a novel closure cap adapted for, but not limited to, the filling or discharge openings of tanks and containers, the device being particularly useful to add to the safety factors of an enclosing lock cap for the protection of said openings.

The invention will be described with reference to the accompanying drawings, in which

Figure 1 is a sectional elevation of a form of the invention taken on the line 1—1, Figure 2,

Figure 2 is a top plan view, partly broken away,

Figure 3 is a bottom plan view of the closure cap per se,

Figure 4 is a reduced horizontal section on the line 4—4, Figure 1, locking in the direction of the arrows,

Figure 5 is a fragmentary view in elevation showing a locking face of the locking cap and lock barrel carried thereby,

Figure 6 is a bottom plan view of the locking cap, showing one of its members swung outwardly,

Figure 7 is a schematic view in elevation, showing a tank, fragmentarily, and the closure and locking caps moved upwardly, both being connected to a chain leading to a stop ring within the neck of the tank.

Figure 8 is a fragmentary plan view showing the barrel receiving end of one locking cap rim member,

Figure 9 is a fragmentary view showing the key receiving end of one locking cap rim member, in elevation,

Figure 10 is a sectional elevation of a modified locking cap, taken on the line 10—10, Figure 11,

Figure 10a is a perspective view of the threaded stud 28 and the chain suspended therefrom.

Figure 11 is a bottom plan view of the structure shown in Figure 10,

Figure 12 is a sectional elevation taken on the line 12—12, Figure 11,

Figure 13 is a bottom plan view of a further modification of the locking cap, partly in section, on the line 13—13, Figure 14,

Figure 14 is a sectional elevation on the line 14—14, Figure 13,

Figure 15 is a sectional elevation on the line 15—15, Figure 13,

Figure 16 is a horizontal section on the line 16—16, Figure 14, locking in the direction of the arrows,

Figure 17 is a schematic perspective view showing the lowermost of the relatively rotatable lug-carrying disks and the adjustable lugs therefor,

Figure 18 is a top plan view of a locking cap

like that of Figure 10 with water drainage channels.

The characteristic of my device is the provision of a closure cap in which (a) the latching lugs are rotatably connected to the cap so that when the latter is associated with a surmounting and surrounding locking cap, the danger of transmitting releasing rotation of the latter to the closure cap is avoided; (b) the improvement of adjustable lugs to accommodate tank opening flanges of different sizes; (c) the provision of two sets of lugs relatively movable away from and toward each other after the cap is applied to further add to the safety of the device; (d) the formation of the closure cap for association with a chain and latching ring, whereby the closure cap, and also a locking cap, may permanently be associated with a tank or other container, to avoid loss of the cap or caps; (e) structural improvements hereinafter set forth.

Referring to the drawings and Figures 1 to 4, I have indicated at 1 a tank or other container having, in this instance, an opening surrounded by an upstanding neck 2, which has the usual ring flange 2x, which in practice is formed with oppositely related apertures (not shown) to receive the latching lugs of a closure cap.

The primary body member of the closure cap is shown at 3, its upper wall being formed with a cup-like depression at 3x, which depression is centrally apertured to receive and provide a bearing for the shank of a thumb piece 4, threaded at its lower end into the threaded aperture of a disk 5. Disk 5 carries two locking lugs, the lugs being relatively adjustable. The first lug, shown at 6 is carried by a plate 6x, having elongated apertures at a to receive screws 7 and a headed stud 8, on which is threaded a nut 9, Figure 3.

The second lug 10 is carried by plate 10x having an elongated aperture to receive headed stud 11 on which is threaded a nut 12. By loosening the screws 7 and nut 9 plate 6x may be adjusted longitudinally, and by loosening nut 12 plate 10x may be adjusted longitudinally. This will accommodate the lugs to the openings of filling neck flanges when the latter are of various diameters.

In the use of the device the closure cap is applied to the flanged neck of the container in such manner that the lugs 6 and 10 project downwardly through openings customarily formed in said flange, whereupon thumb piece 4 is rotated to move the closure cap so as to carry the lugs under the wall of the neck flange thus securing the cap firmly in place, by such rotation

of the thumb piece not only would the lugs 34 be offset from the lugs 36 but the cap as a whole may be rotated.

A sealing ring 12x of rubber or other suitable material may be employed immediately above the lugs 6 and 10 to bear upon the upper face of the filling neck ring flange.

The locking or protector cap for the closure cap may be of the type shown in my United States Patent No. 2,131,060 of September 27, 1938, and is so illustrated in the drawings, but somewhat modified as now to be explained.

The protector cap may comprise an upper disk-like member 13 having an integral semi-annular wall 14, wall 14 at one end having a locking socket extension 14x and at the opposite end a pin hinge at 15 (Figure 6) to receive a hinged side wall 16 having a locking barrel holding end 16x enclosing barrel lock mechanism of any desired type. The lower face of locking cap wall 13 has pivotally connected thereto by headed stud 17 a rotatable spring spider 18 which, when the closure cap is in position immediately contacts with and bears against the top closure cap. This is a safeguard against such frictional engagement of the closure cap with the locking cap as to enable rotation of the former by pressing downwardly upon the locking cap and giving it a rotary movement. In such case the spider fingers will be more or less bound to the locking cap but the closure cap will rotate upon headed stud 17 as an axis.

In order that disk 5 carrying lugs 6 and 10 may have only a limited movement, I prefer that the openings in the depressed cup-like wall of the closure cap body 3 through which headed studs 8 pass be as shown in Figure 4, i. e., short arcuate openings, the ends of which will stop the studs against any but limited lateral movement.

The broken-away plan view shown in Figure 2 illustrates the relation of the parts when in position. It will be seen that the lower inwardly projected flanges 14x, 16x of members 14 and 16 carry antifriction rollers 19 adapted to bear upon the lower rim of the closure cap if any attempt is made to move the latter by pulling the locking cap upwardly to secure frictional engagement with the closure cap at the base thereof and thereby, through rotation, removing it from the neck of the container.

As shown in Figures 1 and 7 the thumb piece 4 may be centrally apertured for the passage of a chain 20 connected at its upper end to headed stud 17 and at its lower end to a stop member, which may be formed as a ring, as indicated at 21.

In Figures 10 to 12 inclusive, I have shown an arrangement in which the locking lugs 22 are of a form different from that in the preceding figures and in which both the locking lugs and overlying spring fingers 24 are endwise adjustable. Both the locking lugs and the spring fingers 24 engage under the flange 2x of the tank neck to hold the closure cap on the neck. In the said modified construction the locking lugs are angularly bent at their ends, the opposed lugs being shown at 22, Figures 11 and 12, and secured to an integral annular extension 23x of the modified form of closure cap 23, the latter being preferably cut with seats to receive the lugs generally in the manner shown in Figure 17. The lugs therefore are movable endwise relatively to the member 23x. The lugs, which have elongated slots in their portions rearwardly of their angularly bent ends are held in place by 70

the underlying shank 24x of a plate spring member 24 longitudinally slotted to receive a holding screw 25 threaded into member 23x and by screws 26 which pass through elongated slots in the shank 21x of a plate spring member 27, the screws also passing through the elongated slots in the lugs. When screws 25 and 26 are loosened, both the spring members and the lugs may be lengthwise adjusted to accommodate container neck flanges of different diameters with different spacings between their lug-receiving openings. If desired, cap 23 may carry supplementary spring fingers or ring 28 above the fingers 24 as shown in Figure 10. Member 23x may be centrally apertured and threaded to receive a chain holding threaded stud 29 to carry the wire (or chain) 30, more particularly shown in Figure 10a. The center of cap 23 may be depressed to receive the head of stud 29 and in such case any water which may pass into the depression will flow outwardly through channels at 29x, Figure 18.

In the construction of Figures 13 to 17 inclusive, two sets of lugs are provided which, when the cap is applied to the flange neck of the container enter flange openings therein which may be somewhat wider than ordinary, and then the cap may be turned and the lugs relatively moved so that even if the cap has moved to inwardly applying position through abnormal friction interposed between the closure and over-all locking caps, the unauthorized removal of the closure cap will be prevented and the closure cap may only be operated for removal by release therefrom of the closure cap and the relative rotation to initial position of the lugs.

For the purpose referred to above, the closure cap of Figures 13 to 17 has the general formation of that shown in Figure 1 and bears like numeral designations. Keyed to the shank of the thumb piece 4 is a rotary disk 31 having arcuate apertures at 31x to receive the screws 32 which are threaded in the depressed wall of cap 3 and which pass through a disk 33 fixed relatively to the cap. Disk 33 is cut away at opposite points to receive lugs 34 having elongated apertures to receive holding screws 35 (Figure 13). Likewise, disk 31 is cut away to receive the lugs 36, the latter having elongated apertures to receive the holding screws 37. By loosening the screws the lugs of either disk may be adjusted to accommodate the various sizes of container neck flanges. At its lower end the shank of the thumb piece is threaded to receive a holding nut 38 as shown in Figures 14 and 15. As shown in Figures 14 and 15, the cap may carry a sealing ring 39 above disk 31 to engage the upper face of the flange neck of the container, the underface of which is to be engaged by the lugs.

When the cap just described is applied to a filling cap, the lugs 34, 36 will be passed through the usual lug-receiving apertures of the filling neck ring flange and the cap may be given a rotation to carry the lugs under the flange, whereupon thumb piece 4 may be rotated to spread the legs away from each other to provide the safety factor desired.

In Figures 8 and 9 I have shown a shield for the key opening 16xx, the shield being shown at 40 being engaged at one end by springs 41 in a recess formed in member 16x, the walls of the recess forming a guide for the movement of the shield. In Figure 7 the shield is split, form-

ing two halves held in normally mutual contact by springs indicated at 42.

It will be understood that the closure cap is adapted for tanks and containers in general, including fuel tanks, barrels and drums, wine and liquor containers, and is also adapted as a locking cap for general purposes.

Having described my invention, what I claim and desire to secure by Letters Patent, is as follows:

1. A closure cap comprising a body member formed with a cuplike depression, a carrying member mounted for rotational movement below the cap, a thumb piece disposed in said cuplike depression and having a rotatable shank secured to said carrying member, a set of latching lugs endwise movable in slots formed in the carrying member, and having elongated apertures, set screws passing through the elongated apertures and into the carrying means for clamping the latching lugs in adjusted position, and a second set of lugs on said body member, whereby rotation of the thumb piece will bodily swing

the first named set of lugs relatively to the second set of lugs.

2. A closure cap adapted for closing the filler opening of a tank of that type in which the opening is provided with an inwardly directed flange formed with clearance passageway for lugs carried by the cap, said closure cap comprising a body member formed at its top with a depending cuplike depression, a rotatable plate disposed below the cuplike depression, a thumb piece having a shank passing through an opening in the lower wall of the cuplike depression and secured to the plate for rotation thereof, lugs mounted on the underside of said plate and extending radially with respect to the axis thereof, means adapted to limit the degree of rotation of the plate, and yielding pressure means carried by the assembly below the cuplike depression and above said lugs and adapted, when the cap is applied to the filler opening, to hold the lugs yieldingly against the underface of the filler opening flange.

ASSAD M. MALLUK.
